KNITTED SWEATER

Louis H. Mendelsohn, Paterson, N. J.

Application January 24, 1956, Serial No. 39,900

Term of patent 3½ years

(Cl. D3—4)

Figure 2 is an enlarged fragmentary front view thereof, at an angle of 90° with respect to the showing in Figure 1, illustrating the knit of the front panel.

The back portion of the sweater is conventionally plain.
I claim:

The ornamental design for a knitted sweater, as shown and described.
